(57) **CLAIM**

I claim the ornamental design for a multi-function copying machine, as shown and described.

DESCRIPTION

FIG. 1 is a top perspective view of a multi-function copying machine of the present invention;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross-section view taken along the line 8—8 of FIG. 2;

FIG. 9 is a cross-section view taken along the line 9—9 of FIG. 2; and,

FIG. 10 is a cross-section view taken along the line 10—10 of FIG. 2.

The broken lines depict environmental subject matter only and form no part of the claimed design.
